UNITED STATES PATENT OFFICE

FRANK A. GERARD, OF DULUTH, MINNESOTA

DEVICE FOR FOOT PROTECTION

Application filed August 9, 1928. Serial No. 298,553.

This invention relates in general to shoe guards, and in particular to that type of shoe guard worn by steel workers and others engaged in kindred occupations, in order to protect their feet from heavy falling objects and from excessive heat or contact with hot metal.

In the accompanying drawings, which illustrate one form of my invention—

10 Figure 1 is a perspective view of the guard positioned on a shoe, and

15 Figure 2 is a longitudinal section of the guard. In this figure the movement of the instep section of the guard in walking is illustrated by dotted lines.

20 Referring to the figures, it will be seen that the guard consists of the pressed metal toe cap 1, the pressed metal instep shield 2, the flexible sole 3, to which the aforementioned shields are fastened by means of rivets 4, and the adjustable straps 5 and 6 for securing the guard assembly to the foot. The instep shield 2 is flared at edges 9 and 10 as illustrated to 25 permit flexibility in walking without making this section too cumbersome.

The safety foot guard is held in place by means of the two canvas straps 5 and 6, which are provided with adjustable buckles. Strap 5 passes through openings 7-7, located on 30 either side of shield 2, passes under the arch on the shoe and over the instep; strap 6 is inserted through holes 8 and passes around the back of the shoe.

35 This guard is designed so that when worn, there is a space between the guard and the shoe, so that if a heavy object should fall on the guard, it would not crush the foot.

40 The advantages of this guard are: first, flexibility while walking; second, the guard being riveted to the sole insures it from slipping back on the toe of the shoe; third, the heavy flexible sole affords ample protection; fourth, this guard gives complete protection to the toes, instep and sole of the foot.

45 Having described my invention what I claim as new is:

1. A foot guard, comprising a metallic toe cap, a metallic instep shield separate from the toe cap, a flexible sole, and means securing 50 said cap and said shield to said sole where-

by relative movement between said cap and said shield may take place by flexure of said sole.

2. A safety shoe guard, comprising a metallic toe cap, a metallic instep shield separate from the toe cap having a portion overlapping said toe cap, a flexible sole, and means securing said cap and shield to said sole whereby relative movement between said cap and said shield may take place by flexure of said sole.

3. In a safety shoe guard, a metallic toe cap, a metallic instep shield separate from the toe cap, said shield including a flared edge overlapping said toe guard, a flexible sole, means securing said cap and said shield to said sole whereby relative movement between said cap and said shield may take place by flexure of said sole, and means for securing the assembly to a shoe.

Signed at Duluth, Minnesota, this 2nd day of August, 1928.

FRANK A. GERARD.
